UNITED STATES PATENT OFFICE.

EMORY J. LIPPS, OF FOUNTAIN HILL BOROUGH, PENNSYLVANIA.

THREAD-TRAVERSE MEANS FOR WINDING-MACHINES AND THE LIKE.

1,240,352.

Specification of Letters Patent. Patented Sept. 18, 1917.

Application filed January 22, 1917. Serial No. 143,563.

To all whom it may concern:

Be it known that I, EMORY J. LIPPS, a citizen of the United States, residing at borough of Fountain Hill, in the county of Lehigh and State of Pennsylvania, have invented certain new and useful Improvements in Thread-Traverse Means for Winding-Machines and the like, of which the following is a specification.

10 This invention relates to means for winding thread or other textile strands with a traverse, as in winding, doubling, spinning and the like, and including a rotary spool or other receiving device on which to wind the 15 material, a traverse rail or other carrier reciprocating substantially parallel with the axis of the receiving device and a thread guide carried by and reciprocating with the carrier opposite the receiving device. For 20 various reasons, depending on the kind of work being done and similar conditions, it is inexpedient to fix the thread guide in permanent relation to the carrier, and so it is usually arranged to be adjustable thereon 25 longitudinally of its path of reciprocation, as by securing it thereto adjustably by screws passed through slots in the thread guide or by springs attached to the carrier and clamping the thread guide thereto. 30 Such expedients are known to be very unsatisfactory. The carrier is assumed to have a throw equal to a given length on the receiving device (usually from inside to inside of its flanges, if it take the form of an 35 ordinary spool, as is usually the case), and the thread guide is supposed to be adjusted on the carrier so that at each limit of its movement therewith its guiding point will be exactly opposite the corresponding end 40 of said length on the receiving device. This would be entirely satisfactory if in practice it were not the case that the receiving device is frequently not held against but is susceptible of appreciable movement longitudinally of its axis in its bearings, or that the 45 thread guide is not always properly adjusted on the carrier with reference to the receiving device, or that, if it is properly adjusted, it works out of place or becomes displaced 50 accidentally.

The result in actual practice of any failure of the receiving device and the traverse throw of the thread guide to be related properly to each other is inferior product, 55 involving in the case of receiving devices in the form of spools or other flanged devices

a large percentage of waste, because the layers of windings being shifted out of place one way or the other the wound mass builds up with a channel next to one flange and an 60 elevation next to the other, and since this elevation when the spool is completely filled has no flange-support it readily slips endwise off the wound package in handling and the thread it represents must be discarded. 65

In place of arranging the thread guide on the carrier in fixed, though adjustable, relation thereto I mount it thereon so as to be freely movable longitudinally of its reciprocating path and provide means to limit in 70 each direction its movement with the carrier. If the rotary receiving device is perchance suitably held against appreciable movement longitudinally of its axis, as in certain instances may be the case, said means 75 is arranged immovably on the frame or other support. If it is not so held, then said means is confined by said device against movement relatively thereto longitudinally of its axis, as by bearing against the ends 80 thereof.

I have shown in the accompanying drawings both of the above stated forms of my invention, each of which may be constructed in various other ways than as shown without 85 departing from the spirit of the invention,

Figures 1 and 2 being a side elevation, partly in section, and a plan of the first form;

Fig. 3 a plan of the second form; and 90

Figs. 4 and 5 a front elevation and a transverse section of the thread guide and carrier.

Referring, first, to Figs. 1 and 2: *a* is a suitable support including brackets *b* in 95 which to support the receiving device and brackets *c* in which the thread guide carrier reciprocates. *d* is the receiving device, having a flange *d'* at each end and being therefore in the present instance an ordinary 100 spool; its axial spindle *e* is journaled in the brackets *b*, and carries a driving whirl *f*. The spool may be driven from a drive-wheel *g*, on a shaft *h* journaled in the frame, by contact of its whirl therewith. *i* is a bar, 105 arranged in brackets *c*, over which the thread extends to the spool from its source of supply (not shown). *j* is the traverse rail or thread guide carrier arranged to be reciprocated by suitable means (not shown) in 110 the brackets *c*. The spool and traverse rail are arranged horizontally; the elements so

far described being those of a well-known type of horizontal winding machine. The spool in this instance is supposed to be held against any appreciable movement longitudinally of its axis (see Fig. 2).

5 *k* is the thread guide, the same having a guiding notch *k'* and, on each side thereof, the impact face *k''*. It is freely slideable on the traverse rail, being in the present instance retained on the same by the front and rear cheek pieces *l* attached to the traverse rail.

10 The means to limit in each direction the movement of the thread guide with the traverse rail is in the present instance a fork-shaped piece *m* which is attached to the frame so that its ends project over the traverse rail. The plane of the inner face *m'* of each such end is distanced from the plane 15 of the inner face of the adjoining spool flange the same as the vertical planes in which lie the guiding notch *k'* and either impact face *k''* of the thread guide.

15 The pressure of the thread being wound on the thread guide keeps up sufficient friction between the latter and the traverse rail so that the thread guide tends to remain in one place on the traverse rail. Since the effective distance between the faces *m'* of the 20 means *m* is equal to the actual distance between the inner faces of the spool flanges the guiding point (notch *k'*) of the thread guide is made on movement of the latter in each direction to come in direct alinement with the inner face of the corresponding spool flange; for, if, as by shifting of the thread guide on the rail from any cause, it would otherwise be carried so far in either direction that its guiding point would pass the 25 inner face of the spool flange, the thread guide will be checked with its guiding point registering with the inner face of said flange by contact with the adjoining face *m'* of the means *m*, sliding on the rail till the latter completes its movement. Thus throughout the winding the layers are made to terminate all in the same plane at each end of the mass of windings.

30 Referring to Fig. 3: Here the parts are all the same as described above excepting the means to limit in each direction the movement of the thread guide, and excepting, also, that the receiving device is susceptible, as shown, of longitudinal movement in its

bearings. In this case, the receiving device 55 being capable of such movement, the said means, being a fork-shaped piece (*n*) as before, is slideable in a holder *o* attached to the frame, its ends bearing against the ends of the receiving device, which it hugs rather 60 closely; the piece *n* is kept horizontal by a pin-and-slot connection *p* with its holder *o*. Here, again, the plane of the inner face *n'* of each end of the piece *n* is distanced from the plane of the inner face of the adjoining 65 spool flange the same as the vertical planes in which lie the guiding notch *k'* and either impact face *k''* of the thread guide.

70 The result of this arrangement is obviously the same as that first described, the means to limit the movement of the thread guide being here confined against movement relatively to the receiving device longitudinally of its axis directly by said device instead of both being confined against such 75 movement by the supporting structure.

Having thus fully described my invention, what I claim and desire to secure by Letters Patent is:

1. Means for winding thread with a traverse including, with a support, a rotary receiving device on which to wind the thread, a thread guide carrier reciprocating substantially parallel with the axis of the receiving device, a thread guide carried by 80 and normally reciprocating with the carrier opposite the receiving device and free to move on the carrier longitudinally of its reciprocating path, and means to stop in each direction the reciprocating movement 85 of the guide with the carrier.

2. Means for winding thread with a traverse including, with a support, a rotary receiving device on which to wind the thread, a thread guide carrier reciprocating substantially parallel with the axis of the receiving device, a thread guide carried by 90 and normally reciprocating with the carrier opposite the receiving device and free to move on the carrier longitudinally of its reciprocating path, and means, confined by said device against movement relatively thereto 95 longitudinally of its axis, to stop in each direction the reciprocating movement of the guide with the carrier.

100 In testimony whereof I affix my signature.

105
EMORY J. LIPPS.
